UNITED STATES PATENT OFFICE.

ARTHUR J. HOLMAN, OF BOSTON, MASSACHUSETTS.

PROJECTING APPARATUS FOR MOVING-PICTURE MACHINES.

Application filed April 23, 1923. Serial No. 633,925.

My invention relates to that type of projecting apparatus wherein the film strip is kept continuously in motion and the effect of said motion is so compensated by means of moving optical rectifying elements as to produce a steady image. The special objects of my invention have been to provide an improved framing means whereby the operator may center the image position on the screen or "frame" while the apparatus is in operation and subsequently focus without disturbance to framing adjustment and without the necessity for moving the optical system along the optical axis; also, to provide means to accommodate the optical system to any degree of shrinkage of the film strip; also, to provide a diaphragm system which will, while providing maximum illumination on the screen, limit the distortion of the image resulting from the variation of equivalent focal length inherent in revolving optical rectifying systems and, furthermore, cut off undesirable marginal rays and eliminate flicker; also, to provide means conveniently to adjust and maintain in exact registration the optical rectifying elements. It has also been my object to provide a certain improvement for such devices wherein the optical rectifying elements consist of oppositely rotating discs, the peripheries of which are composed of sectors of lenses, prisms, or other variable refracting elements, which improvement consists in providing opaque areas to prevent the passage of light through parts of the system which because of temporary angular position are not of correct refracting power. For devices of the character specified wherein the optical rectifying elements consist of oppositely rotating discs the peripheries of which are composed of sectors of lenses I have sought to provide an improved means of mounting the several sectors and have also sought to provide an improved means for focusing and securing correct registration of images on the screen without the necessity of moving the revolving discs along the optical axis.

My invention may be best understood by reference to the accompanying drawings in which—

Fig. 1 is a front view of my device.

Fig. 2 is a front view with the front objective mount and front housing removed.

Fig. 3 is a cross section on line 3—3 of Fig. 1, viewed in the direction of the arrow.

Fig. 4 is a cross section on line 4—4 of Fig. 1, viewed in the direction of the arrow, with the right side door open.

Fig. 5 is a cross section on line 5—5 of Fig. 6, viewed in the direction of the arrow, showing means for adjusting and maintaining in exact registration the optical rectifying elements.

Fig. 6 is a left side view with the left side doors removed, showing the actuating gear train and automatic fire shutter control mechanism.

Fig. 7 is a back view with the rear casing and side doors removed, the lower sprocket bearing and part of the idler bracket being cut away.

Fig. 8 is an enlarged view of the film actuating and framing mechanisms shown in Fig. 4 with the framing device set to advance the film and thereby raise the image position on the screen.

Fig. 9 is a plan view of the aperture unit.

Fig. 10 is a longitudinal cross section of the upper guide roller located above the aperture plate for guiding the film strip across the aperture.

Fig. 11 is a left side view of the aperture unit.

Fig. 12 is a horizontal section of the aperture unit on line 12—12 of Fig. 13.

Fig. 13 is a vertical section of the aperture unit on line 13—13 of Fig. 9.

Fig. 14 is a vertical section showing construction of the aperture unit sprocket support.

Fig. 15^A is a view of the rear diaphragm.

Fig. 15 is a diagrammatic illustration of the method of arriving at the shape and size of the aperture in the rear diaphragm.

Fig. 16 is a diagrammatic illustration of the optical influence of the optical system when the optical centers of complementary lens sectors in the revolving system coincide with the optical axis.

Fig. 17 is a diagrammatic illustration of the optical influence of the optical system when radial edges of complementary lens sectors overlie on the optical axis.

Referring now more specifically to the drawings, in which like reference numerals indicate like parts, 1 is a metallic base plate from which rises a web 2 (see Fig. 7) which carries the main drive shaft bearing 3 in which rotates the drive shaft 4. Fast on the drive shaft 4 is mounted gear 5 which has integral therewith the film take-up drive

pulley 6. The drive shaft 4 is actuated by pinion 7 which meshes with gear 5. The pinion 7 is fast upon a hollow shaft 8 carrying friction disc 9 to which motive power is directly applied. The hollow shaft 8 is supported upon a stud 10 (see Fig. 1) which enters boss 11 integral with base 1 and is retained therein by set screw 12. The shaft 4 is provided with a sleeve 13 fixed thereon. The sleeve 13 has a shoulder 14, 10 which may engage a similar shoulder on a hand crank whenever manual operation is desired.

15 *The actuating mechanism for the optical rectifying system.*

A counter-shaft 15 supported by bracket 16 on web 2 has fixed thereto a pinion 17 which meshes with gear 5. The counter-shaft 15 also bears fast thereto the gear 18 which meshes with gear 19 fast on cross-shaft 20 (see Fig. 5). Cross-shaft 20 is mounted in the following manner: A transverse web 21, secured to base 1 and also to web 2 by means of screws 22 passing through lugs 23 on web 2, has cast integral therewith the lower portions of worm wheel cases 24 and 25. The upper portions 24^a and 25^a are cast integral with the bearing caps 26 and 27 respectively and are held in position by screws 28. (See Figs. 5 and 6.) The cross-shaft 20 is mounted in bearings in the lower portions of worm wheel cases 24 and 25 in the following manner: In the lower portion 30 of case 24 are fixed by pressed fitting bronze bushings 29 and 30 which support the left end of the cross-shaft 20 and maintain the worm 31 which is fixed to cross-shaft 20 in operative contact with worm wheel 32. In the lower portion of the case 25 are press fitted internally threaded steel bushings 33 and 34 into which screw bronze bearing bushings 35 and 36 which shoulder against opposite ends of worm 37 fixed to cross-shaft 35 40 and maintain worm 37 in operative contact with worm wheel 38. Bronze bearing bushings 35 and 36 are provided with hexagonal ends 35^a and 36^a whereby these bushings may be screwed inwardly or outwardly 45 so as to throw the cross-shaft 20 slightly to the right or left for a purpose to be herein-after specified and to prevent end play of this shaft. When bushings 35 and 36 are set in proper position they may be locked by lock nuts 39 and 40. Upon the left end 50 of cross-shaft 20 is mounted a fly wheel 41.

The worm wheels 32 and 38 are mounted respectively by forced fit upon shafts 42 and 43, the hubs of said wheels being journaled in the cases 24 and 25. The shafts 42 and 43 extend forwardly (see Figs. 2, 3, and 4), their front extremities being journaled in bosses 44 and 45 on frame 46 which is secured to bosses 47 on the front of web 21 by means of screws 48, after being positioned

by dowel pins 49 on the ends of bosses 50, also on the front of web 21. In the center of frame 46 there is a circular aperture 51. The shafts 42 and 43 protrude beyond their bearing bosses 44 and 45 and are provided with collars 52 and 53 which are set-screwed in position so that these collars prevent end play of the shafts 42 and 43. 70

75 *Optical rectifying system.*

Fast mounted upon each of shafts 42 and 43 are annular spiders 54 and 55 made of cast iron. These spiders 54 and 55 support each an annular glass disc made up of a plurality of uniform sectors 56. Each of these sectors 56 is cut from a lens blank and the sectors are so arranged that their optical centers are equidistant on a common circumference, the lenses being all of uniform focal length. The lens sectors 56 are secured to the spiders 54 and 55 in the following manner: A plurality of clamps 57 equal in number to the number of lens sectors 56 are attached to the spiders 54 and 55 by screws 58 which may be tightly set up, thus clamping the lens sectors securely in position. These clamps 57 are seated against annular shoulders 59. It will be noted from examination of Figs. 2 and 3 that the spiders 54 and 55 and the elements carried thereon are oppositely faced so that the curved faces of the lens sectors 56 adjacent where the lens sectors of the respective revolving elements overlap in the zone surrounding the optical axis, which passes through the center of aperture 51 in frame 46. The lens sectors 56 have their radial edges ground to such an angle that they will fit together to form a complete ring with a minimum space between the several sectors. Each of the sectors 56 has on its curved side an area over which the clamp 57 fits, which is ground parallel to the plane side, thus ensuring that the plane surfaces of all sectors in a ring or disc will lie in a common plane which is perpendicular to the shaft whereon the disc is mounted, and also ensuring that the pressure on the glass will be applied normally to the surface. Between the clamp 57 and the 100 glass and between the spider and the glass I place on either side a piece of thin paper which forms a yielding pad to distribute pressures due to slight irregularities in opposing surfaces. These paper pads are 105 also useful as insulators to prevent excessive heat transfer from the glass to adjacent metal parts. Between the clamps 57 are placed dowel pins 60 for the purpose of preventing dislocation of the clamps by side shifting when screws 58 are being set up. It will be understood that the assembling and adjustment of the lens sectors comprising the disc are performed previous to mounting the disc in the machine. When the discs are in 110 position upon their respective shafts the com- 115

mon circles whereon lie the optical centers of the lens sectors pass through the optical axis. The relative angular positions of complementary lens sectors on each disc are such that their optical centers coincide simultaneously with the optical axis. Located adjacent to the outer periphery of the discs and symmetrically placed across each pair of adjacent radial edges of the lens sectors 56 is a small patch 61 of opaque material such as black linen adhesive tape of substantially the relative size and shape shown in Fig. 2. These patches 61 are shown as placed preferably on the curved side of each lens sector so that they may be as near as possible to the equivalent center of the revolving system. The function of these patches 61 will be later described.

Projecting forwardly from the frame 46 is a pair of studs 62 and 63 which are parallel to each other and to the shafts 42 and 43 and located on either side of the aperture 51. Directly above the aperture 51 is a rack 64 supported by a flanged base 65 which is attached by screws to the face of frame 46. A cylindrical front objective mount 66 is slidably supported upon studs 62 and 63 which pass through bores in lugs 67 and 68 cast integral with said mount 66. A boss 69 (see Figs. 1 and 4) on the top of mount 66 and parallel to the axis thereof is channeled to receive the rack 64 and is provided with a cover plate 70. At right angles to this boss 69 is a boss 71 bored to receive a rotatable pinion shaft 72 provided with pinion 73 which meshes with rack 64. A knurled handle 74 is mounted on the end of shaft 72. By turning handle 74 the front objective mount 66 may be moved along the optical axis in either direction.

Within the front objective mount 66 there is slidably fitted the lens tube 75, the inside of which is threaded at the rear end to receive the lens supporting ring 76 which carries the front objective 77. Fastened by screws to the rear of the front objective mount is a rear diaphragm 78 (see Fig. 14) having an aperture 79 which is circular except for V-shaped projections 80 and 81 on the upper and lower parts of the diaphragm respectively. The function of this diaphragm 78 will be later specified. In the front end of objective mount 66 is slidably inserted a tube 82, the front end of which is threaded to receive diaphragm ring 83 in which is mounted the front diaphragm 84 which is retained in place by a threaded collar 85 which is screwed into the interior of the ring 83. The diaphragm 84 has an aperture 85 the sides of which correspond in curvature and alignment with the outer peripheries of the revolving discs made up of lens sectors 56. The vertical dimension of the aperture 85 diminishes gradually toward its center, its shape being as shown

in Fig. 1. The function of this aperture will be later described.

Means for actuating the film strip and adjusting its position relative to the optical system.

The web 2 (see Fig. 7) carries integral therewith the lower sprocket bearing 86 in which rotates shaft 87 driven by gear 88 which meshes with gear 5. On the opposite end of shaft 87 is mounted the lower sprocket 89 of conventional form designed to engage the perforations in the standard film strip. The film strip is held in engagement with the sprocket teeth by idler roller 90, of conventional design, which is supported by a swinging bracket 91 (see Fig. 4) pivoted on screw 92 which enters web 2. The bracket 91 carries a pin 93 which bears upon a jack-knife spring 94 designed to retain the idler roller 90 either in or out of operative position.

Fast upon shaft 87 is a helical gear 95 which actuates vertical shaft 96 through helical gear 97 which is fast on shaft 96. The shaft 96 is supported by a bearing in boss 98 integral with web 2. The top of shaft 96 is supported at its upper end by a bearing in bracket 99 attached by screws to a boss 100 on the top of web 2. The shaft 96 bears, near its top, a helical gear 101 which meshes with a helical gear 102 fast on the upper sprocket shaft 103 which has a bearing in boss 104 on web 2. This upper sprocket shaft 103 bears the conventional sprocket 105 similar to the lower sprocket 89 and in alignment therewith. The sprocket 105 has an idler roller 106 which is supported by a swinging bracket 107 pivoted on screw 108 which enters web 2. The bracket 107 carries a pin 109 (see Fig. 8) which bears upon a jack-knife spring 110 designed to retain the idler roller 106 either in or out of operative position. The brackets 91 and 107 are each provided with a set screw 111 and lock nut 112 which limit the movement of the idler rollers toward their respective sprockets, thus preventing undue pressure on the film strip.

Integral with the transverse web 21 are bosses 113 and 114 (see Figs. 5 and 11) which have bores parallel to each other and to the optical axis in which are slidably mounted rods 115 and 116 which are fixed to the aperture mount 117. Mounted on the side of the aperture mount 117 is a rack 118 which meshes with a pinion 119. This pinion 119 is fast on rod 120 (see Fig. 7) which is provided with bearings in offsets in web 2 and extends vertically upward through top casing 121, terminating in hand wheel 122. By turning the hand wheel 122 the aperture mount 117 and all parts carried thereby may be moved forward and back

along the optical axis. An aperture plate 123 (see Figs. 12 and 13) is attached by screws to the rear of the aperture mount 117. This plate 123 is provided with tracks or curved shoes 124 on either side of the aperture. The height of the aperture formed by the plate 123 is approximately two and three-quarters times the height of a film picture. Journaled in lugs 125 and 126 (see Figs. 9 and 10) in the top of aperture mount 117 is a shaft 127 which has fixed thereto the roller 128. This roller 128 has a side flange 129 integral therewith whereas the opposite flange 130 is integral with a detached portion 131 of roller 128. The detached portion 131 is free to slide on shaft 127 and is made to rotate with roller 128 by means of the pin 132 which is fixed in detached portion 131 and enters a clearance hole in roller 128. The detached portion 131 is forced toward the roller 128 by spring 133 which shoulders against the enlarged end 134 of shaft 127. The opposite end of shaft 127 is supported by threaded bearing bushing 135 which screws into lug 126. The bushing 135 contacts on its outer end with the collar 136 which is pinned to shaft 127 and on its inner end with roller 128. By turning bushing 135 by means of its knurled annular flange 137 the roller 128 may be shifted transversely to the optical axis and may be locked in a desired position of transverse adjustment by means of the lock-nut 138.

35 Mounted in forked lug 139 (see Fig. 14) at the bottom of aperture mount 117 is shaft 140 which carries a sprocket 141 in alignment with sprockets 105 and 89. This shaft 140 is actuated by a gear 142 fast thereon. A bushing 143 fitted closely in forked lug 139 forms a bearing for shaft 140 butting at one end against the gear 142 and at the other end against sprocket 141, thus preventing end play of shaft 140. The bushing 143 is secured by set screw 144. A swinging bracket 145 is pivoted on bushing 143 closely fitting in the fork of lug 139. Mounted on screw stud 146 (see Figs. 11 and 13) which enters a boss 147 on swinging bracket 145 is a pinion 148 which meshes with gear 142 on the sprocket shaft 140. Press fitted on the extension hub of pinion 148 is gear 149. It will be readily apparent that since swinging bracket 145 is pivoted on shaft 140 pinion 148 will remain in operative contact with gear 142 regardless of the angular position of swinging bracket 145.

60 Mounted in a boss 150 on web 21 (see Figs. 4 and 5), which boss has a bore concentric with cross-shaft 20, is a bell-crank 151 which may oscillate in said boss. A stud 152 in the end of said bell-crank forms a bearing for gear 153 which meshes with gear 154, integral with gear 19 which is fast 65 on cross-shaft 20 as previously described.

The bell-crank 151 is provided with a screw collar 155 which shoulders against the right side of boss 150 and prevents lateral movement of the bell-crank and the gear 153 carried thereby. A link 156 pivoted at one end on a screw 157 entering stud 152 and concentric therewith is pivoted at its other end on screw stud 146. The link 156 holds gears 149 and 153 in meshed relation.

Pivoted on a boss 158 (see Fig. 8) extending forward on the front of web 21 is a radius arm 159 which passes through a slot 160 in the web 21. The opposite end of radius arm 159 is connected by means of pivot screw 161 to links 162 and 163, in such a manner that the relative angular positions of the arm 159 and links 162 and 163 may be varied. The link 163 is connected by means of pivot screw 164 with swinging bracket 145. The lower end of link 162 is split to straddle tongue 165 on the end of arm 166, being connected with said tongue 165 by pivot screw 167. The arm 166 is fixed in an annular hub 168 pivotally mounted on a boss 169 on web 2 by stud 170 (see Fig. 6) which is provided with nut 171 which sets against a spring washer 172, thereby providing the necessary friction between hub 168 and boss 169 to restrain the parts actuated through hub 168 from shifting except by manipulation of the handle 173 which enters hub 168. The relative distances between pivotal centers provided by stud 170 and pivot screws 161, 164, and 167 and the pivot in boss 158 are such that for any setting of the handle 173 the aperture mount 117 may be moved along the optical axis by operation of the hand wheel 122 without any rotative influence upon the sprocket 141.

It is to be noted that the lengths of link 163 and the radius arm 159 and the relative positions of their several points of pivoted support are all definitely interrelated and are dependent upon the following geometrical considerations; it is apparent that if aperture mount 117 is to be shifted longitudinally without affecting the speed of the sprocket 141 the movement of the pivot screw 164 must be limited to a path of travel which is substantially an arc. This arc is first determined experimentally by holding gear 154 stationary and restraining sprocket 141 from rotating while shifting aperture mount 117 longitudinally. This will cause the center of pivot screw 164 to describe an arc which may be observed and plotted, and from which can be obtained a radius and a fixed center. The effective length of link 163 is this radius and the position of the pivot screw 161 is the center. It will also be apparent that if gear 154 is held stationary and the sprocket 141 is rotated slightly to a new position and restrained from rotating, and the aperture mount 117 is shifted

longitudinally, as before, the center of pivot screw 164 will describe a new arc requiring a relocation of the center at pivot screw 161. In this way a series of center locations are obtained and plotted and from these are obtained the necessary length of the radius arm 159 and the position of the pivot 158.

Across the top of aperture mount 117 is a transverse boss 174 through which passes a shaft 175. A bell crank 176 (see Fig. 11) is fast on the end of shaft 175. The outer end of bell crank 176 is attached by pivot 177 to link 178 which is attached by pivot 179 to one end of rocker bar 180 which is pivoted on screw 181 which enters aperture mount 117. The opposite end of rocker bar 180 is attached by pivot 182 to one end of link 183, the opposite end of which link is pivoted by screw 184 to gate block 185.

20 Fixed in the gate block 185 is a plunger 186 which enters with a close sliding fit a bore in the aperture mount 117 (see Fig. 12) passing into a cylindrical chamber 187 in a boss 188 on the side of the aperture mount 117. A plunger head 189 on the end of plunger 186 is formed to have a free sliding fit in the chamber 187. A coil spring 190 confined between the bottom of the chamber 187 and plunger head 189 normally holds the gate block 185 in extreme forward position. Guide rods 191 and 192 which are fixed in gate block 185 enter bores in pins 115 and 116 respectively and maintain the gate block 185 in vertical position.

25 To move the gate block 185 rearward to the open position illustrated in Figs. 12 and 13 downward pressure is applied to arm 193 which is pinned to shaft 175. The arm 193 is provided with a knurled grip 194. A pin 195 mounted in the side of aperture mount 117 is so positioned as to contact with the rocker arm 180 as its lower end comes into alignment with link 183 thereby automatically locking the gate block 185 in extreme rearward position. A slight upward pressure on grip 194 immediately releases the block 185 from the locked position thus permitting spring 190 to return the gate block to its forward position.

30 The gate block 185 is provided with a vertical slot 196 through which pass the guide rods 191 and 192 forming supports in the slot for the gate frame 197 which bears integral lugs 198 and 199 (see Fig. 7) which are slotted to hook over said guide rods 191 and 192 thus holding the gate frame 197 rigidly to the gate block 185. The gate frame 197 is thus removably mounted. Hinged on pin 200 which passes through lugs 201 and 202 on the top of gate frame 197 is bracket 203 between the arms of which is mounted the roller 204. A leaf spring 205 secured to the back of bracket 203 and bearing against the top of gate frame 197 actuates the bracket 203 forward so that roll-

er 204 will hold a film strip between the flanges 129 and 130 on guide roller 128. A stop pin 206 mounted in the top of the gate frame 197 limits the forward movement of bracket 203 and prevents excessive pressure of roller 204 against the film strip.

35 Mounted on the bottom of the gate frame 197 is a plate 207 which has a curved portion arranged to embrace sprocket 141. Within slots in said plate 207 are mounted curved pressure fingers 208 which are designed to press upon the film strip on either side of each line of perforations thus retaining the teeth on sprocket 141 in complete engagement with said perforated portions of said film strip. The fingers 208 are spaced and retained in position by pins 209 and 210 and are supported in plate 207 by means of a spring clamp 211 mounted on the back of plate 207.

40 A rectangular frame 212 mounted within gate frame 197 is held in position against lugs 213 and 214 on gate frame 197, which lugs bear upon its transverse portions by means of bow springs 215 and 216 which 45 butt against pins 217 and 218 on the sides of gate frame 197 and also bear against the vertical portions of frame 212. The vertical portions of frame 212 are curved to correspond to the curvature of shoes 124 of the 50 aperture plate 123, and form spring pressure pads to hold the film strip in contact with shoes 124.

45 It is to be observed that the gate frame 197, by virtue of its mounting upon gate block 185, is movable with respect to aperture mount 117, and is also movable in unison with it when hand wheel 122 is turned to actuate pinion 119 and thus move rack 118. To guide rack 118 and maintain it 55 in operative contact with pinion 119 a channeled block 219, which is screwed to web 2, is provided.

50 Slidably mounted on the shaft 96 is a sleeve 220 (see Figs. 6 and 7) which has integral therewith a flange 221 and a cross arm 222. Fixed to shaft 96 above sleeve 220 and spaced apart therefrom is a sleeve 223 provided with a cross arm 224. Two links 225 are hung from the ends of cross arm 224 being pivoted thereto. To each of said links 225 is pivotally attached at its opposite end one-half of a split annular governor weight 226. Links 227 connect said governor weight 226 to the cross arm 222 on sleeve 220, said links 227 being pivotally mounted at each end. Upon the rotation of shaft 96 centrifugal force will separate the split halves of weight 226 and cause the sleeve 220 to be elevated. An arm 228 pivoted at one end by screw 229 to web 2 carries a roller 230 which bears upon flange 221. The arm 228 is pivoted at its other end to link 231 which is pivotally connected with arm 232 which connects with 130

and operates the fire shutter 233 in the usual manner. The fire shutter 233 is slidably mounted in a slot 234 in back of rear casing 235, being supported on each side by rods 236 which are lightly embraced by ears 237 integral with the fire shutter 233. The fire shutter 233 closes an aperture 238 in the back of casing 235 when the machine is at rest, but when the machine is in operation 10 its normal speed will separate by centrifugal force the halves of governor weight 226 causing the flange 221 to lift arm 228, thereby raising the fire shutter 233 and holding it in elevated position, so as to open 15 completely aperture 238 through which passes illumination from a suitable light source, which illumination continues through the optical system.

20 *The casing.*

Hinged to the rear casing 235 is the right side door 239 in which is mounted a glass window 240. A knob 241 operates a snap 25 catch 242 to hold the door 239 in closed position. The top casing 121 has integral therewith a box 243 into the concave top of which may be fitted the usual film magazine. Within this box 243 are mounted the usual 30 valve rollers 244, 245, and 246.

The left side of the mechanism is a casing door 247 at the bottom (see Fig. 1) which is retained in closed position by screw knob 248. Above this door is a casing door 249. 35 The worm wheel cases which are made up of lower portions 24 and 25 and upper portions 24^a and 25^a are covered by plates 250 and 251 which are retained by screws. A casing 252 houses the back and sides of the revolving 40 optical system. This casing 252 is flanged to partially embrace the right side of the device to the rearward of the revolving system. A housing 253 encloses the right hand gear box composed of parts 25 45 and 25^a (see Fig. 3). The front opening of casing 252 is completely covered by housing 254 which is retained in position by thumb screws 255 and by knurled nuts 256 which screw upon studs 257 which are fixed in the 50 casing 252 and pass through holes in the housing 254. In the rear of each side of housing 252 are hand hole covers 258 and 259 which are retained in place by screws 260.

55 *Mode of operation.*

To operate my device power is applied by motor to the friction disc 9 which through the gears described rotates main drive shaft 60 4. Sprockets 105, 141, and 87 will now be rotated in an anti-clockwise direction through their respective gear trains, all revolving at the same speed. The teeth of 65 these sprockets engage the perforations of a film strip which has been inserted between

valve roller 244 and rollers 245 and 246, whence the film strip passes over the rear of sprocket 105 being held in engagement therewith by the idler roller 106. The conventional loop is then formed before the 70 film strip is passed between the flanges 129 and 130 of roller 128 where it is held in position by the roller 204. Next the film strip passes over the shoes 124 of the aperture plate 123, bridging the aperture and being 75 pressed against said shoes by the vertical sides of the rectangular frame 212. The film strip then passes over the rear of sprocket 141, being held in position by the curved pressure fingers 208. The conventional lower loop is then formed in the film strip which passes over and around the back of sprocket 89, being held in contact therewith by idler roller 90. To facilitate this 80 operation of threading the film strip through the mechanism the idler rollers may be thrown back and the gate frame 197 may be thrown open by depressing knob 194. It will be observed that the anti-clockwise rotation of the sprockets causes the downward movement of the film strip.

The starting of the machine at once causes lateral displacement of the two halves of the split weight 226 causing the flange 221 to lift arm 228 and elevate the fire shutter 233, thus opening the aperture 238 and allowing light rays from a condenser system to fall upon the film strip and thence pass through the optical system.

The cross-shaft 20 through worm gear 100 drives connected therewith rotates the lens discs in opposite directions so that overlying portions thereof are moving downwardly. It is to be noted that for positioning the discs with respect to the relative 105 angular positions of their radial portions, so that the radial edges of complementary lens sectors may register with each other on the optical axis as in Fig. 2, a very precise adjusting mechanism is provided through the 110 means described for shifting cross-shaft 20 slightly to the right or left, thus causing sufficient relative shifting of the overlying portions of revolving lens discs to secure the desired registration. The gear ratios of 115 the mechanism are such that one film picture is passed across the optical axis during the time occupied by the passage of a pair of complementary lens sectors across the optical axis. It will be readily understood that 120 the revolving lens discs are a means of providing the variable refraction necessary for retaining upon a screen an image projected from a continuously moving film strip according to an established principle. Heretofore in the application of this principle 125 the image has been successfully retained upon the screen but due to inherent characteristics of optical rectifiers heretofore employed a periodic fluctuation of the image 130

has appeared and this has been of sufficient magnitude to be objectionable. An attempt to overcome this objection has been made through the employment of an outer 5 objective to which is imparted a periodic movement in the vertical plane. This had been partially successful but has itself occasioned an objectionable periodic distortion of the image owing to the fact that the optical axis is thereby periodically shifted. 10

Instead of seeking to correct the inherent periodic fluctuation of the image common to optical rectifiers of this general description, and thereby producing a new disturbance as above stated, I have so constructed my device that I have reduced to a negligible amount the inevitable inherent fluctuation so that the image is practically steady and at the same time free from distortion.

I have done this by reducing the angle A subtended at the center of the revolving discs by an individual lens sector, and also by reducing the angle B (see Fig. 15), the significance of which will be later described.

Thus I limit the extent in variation of the rate of approach to and departure from the horizontal plane passing through the optical axis by the optical centers of the lens sectors, so limiting the amplitude of fluctuation of the image resulting from this variation that when, for instance, the sum of angles A and B is 29 degrees the amplitude of fluctuation of the image covering a screen twelve feet in height does not exceed one-quarter of an inch and is, therefore, not visible to the observer.

Assuming, therefore, that the machine has been put in operation, the image of the film pictures which now appears on the screen is centered on the screen by operating framing handle 173, the functioning of which will hereinafter be described. The image is now focused by operating handwheel 122 and successive images are made to register on the screen by adjusting handwheel 74. Should the latter require a considerable adjustment it will be necessary to slightly readjust the focus by turning handwheel 122.

In order to illustrate the significance of these adjustments it will be assumed that the motor is stopped and the mechanism is operated by slowly turning flywheel 41 until a film picture is centered on the aperture plate 123. With this setting a straight line, which I have called the optical axis, will pass through the center of the film picture, through the optical centers of the pair of complementary lens sectors 56 on the revolving discs, through the optical center of the front objective 77, and through the center of the image on the screen as illustrated diagrammatically in Fig. 16. For simplicity I have represented pairs of complementary lens sectors as well as the front objective by equivalent double convex

lenses. It will be apparent from Fig. 16 that for this particular setting the optical system is identical to that used in conventional projection lanterns, however, because of mechanical construction, focusing is accomplished by adjusting the film position with respect to the optical system instead of adjusting the lens system with respect to a fixed film position as is the case in conventional projection lanterns. 75

Flywheel 41 is now turned till a pair of film pictures are centered on the aperture plate 123. With this setting the optical axis will pass through the center of the space between the pair of film pictures, through radial edges of the lens sectors 56 on the revolving discs, through the optical center of the front objective 77, and through the center of the image on the screen as illustrated diagrammatically in Fig. 17. 80 The solid lines represent the condition of proper adjustment for registration of successive images on the screen. For any position of the front objective too close to the revolving system such as the dotted position shown in Fig. 17 it will be noted that the image will be larger and will no longer be centered on the screen. The film picture which is below the optical axis will have its image center below the center of 90 the screen and the film picture which is above the optical axis will have its image center above the center of the screen. If the front objective is located too far from the revolving system the image will be smaller and again the image centers will not fall on the center of the screen. It will be apparent from an inspection of the construction of the paths of the light rays in Fig. 17 that the axial adjustment of the front objective will permit the registering of screen images no matter what the value of the distance between centers of pictures on the film strip. The picture spacing on any given film strip at a given time will be very uniform but it may differ by 1% or even more from the picture spacing on another film strip due to film shrinkage which varies in amount depending on age of film, chemical ingredients, and previous treatment. I have provided for this front objective axial adjustment to permit correct registration of images for any film strip regardless of amount of film shrinkage. 100 110 115 120

It will be apparent from an inspection of Fig. 2 that the radial edges of a pair of complementary lens sectors 56 coincide only when they lie in the horizontal line connecting the centers of shafts 42 and 43. For all other positions within the zone of light rays these radial edges intersect at a point, the acute angle between the said radial edges being proportional to the distance between this point of intersection and the optical axis. The areas included within

the triangles formed by these acute angles and the portions of the outer peripheries of the discs which they intercept are detrimental to the screen image as long as these areas are within the zone of light rays, because within these areas the lens sectors are not complementary but opposed in refractive power. The opaque patches 61, which are provided to cover these areas, 10 are located with their apexes at the point of intersection of the radial edges of complementary lens sectors at the instant when these radial edges enter the light beam and the angle included between the sides of the 15 opaque patches is double the acute angle formed by the radial edges of the lens sectors at the same instant. The angle of the patch edges is thus increased because on leaving the beam of light the overlapping 20 occurs on the opposite side of the radial edge. Hence, the patch must extend beyond the radial edge an equal amount on each side thereof.

The rear diaphragm 78 which is mounted 25 between the revolving lens system and the front objective serves the purpose of a conventional internal lens stop but differs therefrom by having the V-shaped projections 80 and 81 at top and bottom. These 30 V-shaped projections, while not materially reducing the cross section of the effective beam of light, close the approach of the incoming complementary lens sectors to the optical axis before they enter the unobstructed beam of light. It will be seen that 35 the edge of the V-shaped projection 80 corresponds with the upper edges of the opaque patches 61 for the given angle B (see Fig. 15). The effective aperture for 40 the incoming complementary lens sectors as they advance downward is included between the edge of the V-shaped projection 80 and the upper edges of the opaque patches. In like manner the effective aperture 45 for the other active lens sectors is included between the lower edges of the opaque patches and the edge of the lower V-shaped projection 81. I have noted that 50 there is a periodic variation in equivalent focal length inherent in all revolving optical rectifiers and the magnitude of this variation is a complex function of the angle B. The purpose of these V-shaped projections is, therefore, to reduce this periodic 55 variation in equivalent focal length to a negligible amount. In determining the exact size of the V-shaped projections a balance is struck between the improvement in screen image and the reduction in illumination.

The front diaphragm 84 is located at the narrowest part of the beam of light and serves the double purpose of stopping off objectionable marginal rays and equalizing the 60 total illumination on the screen for all an-

gular positions of the active complementary lens sectors. It will be evident from an inspection of Figs. 16 and 17 that the effective rays of light from any particular film picture pass through the front objective in a 70 particular zone, the vertical position of the zone being dependent on the position of the particular film picture on the aperture plate. It will be understood that as soon as a pair of incoming complementary lens sectors enter the beam of light the particular film picture, which this pair of lens sectors is to project on the screen, will be uniformly illuminated over its entire area. For the position of the complementary lens sectors 75 shown in Fig. 16 the one film picture centered on the optical axis is receiving full illumination from the light source and the full area of the opening in the rear diaphragm is passing effective illumination 80 through to the front objective. For the position of the complementary lens sectors shown in Fig. 17 each one of the pair of film pictures centered on the aperture plate is receiving full illumination from the light 85 source but the effective illumination which reaches the front objective from each of these film pictures must pass through an opening in the rear diaphragm having an area equal to half the area of the opening in 90 the rear diaphragm minus half the area of two opaque patches. I have found that without further modification of the light beam leaving the front objective there will be a periodic variation in the total illumination reaching 95 the screen and consequently a considerable flicker will result. Because of the travelling of the effective zone of the front objective with the downward movement across the aperture plate of the particular film picture 100 which is being projected through the said zone, it is possible to so modify the effective area of the front objective that the total illumination reaching the screen will be constant for all active positions of the complementary lens sectors. This is accomplished 105 by the front diaphragm, the area and shape of the opening in which has been determined more or less experimentally, and is substantially 110 of the relative size and shape shown in Fig. 1 of the drawings. The elimination of the above mentioned flicker by this means is essential to good projection as determined by present commercial standards.

It will be observed that my apparatus is, as I have stated, focused by turning hand-wheel 122 which moves the aperture mount carrying the film strip along the optical axis. Hence, the control of the film actuating mechanism, namely, sprocket 141, which pulls the film strip across the aperture plate must be effective in any position of the aperture mount. I have established this control through the gear and link mechanism operated by handle 173 which by changing the 115 120 125 130

relative positions of the centers of gears 154, 153, 149, 148, and 142 causes a relative rolling of these gears on each other, thereby temporarily, during such operation of said handle, advancing or retarding the speed of rotation of sprocket 141 so as to advance or retire a particular film picture with respect to a pair of complementary lens sectors in the revolving discs, with which sectors it is in-

- 10 tended to function. The link mounting of these gears, as described, maintains them in correct meshed relation by permitting relative rotation incidental to the shifting of their centers whatever may be the longitudinal 15 position of sprocket 141 as a result of focusing operations. It will be apparent that an adjustment of the focusing position of the aperture unit will not affect the speed of rotation of sprocket 141 since the consequent 20 longitudinal movement of the aperture unit causes a relative rolling of the various gears in the link system upon each other, the net result of which is compensating. I have thus provided an effective and easily operat- 25 ed framing means notwithstanding the difficulties encountered because of focusing by longitudinal movement of the film carrying aperture unit, which method of focusing is the only practical method in a device of the 30 optical rectifying type described.

It will be understood, of course, that my device is readily adaptable for use as a camera as well as for use as a picture projector.

- 35 Having thus fully described my invention, what I claim is—

1. In a device of the character specified the combination of an aperture mount provided with an aperture, means for guiding a film strip across said aperture, means whereby said aperture mount is slidably supported in a manner such that its position may be shifted longitudinally, a sprocket on said aperture mount arranged to actuate said film strip across said aperture, a sprocket shaft, a drive shaft, a gear train arranged to actuate said sprocket, said gear train comprising a gear fast on said drive shaft, a second gear driven by said gear fast on said drive shaft, a third gear driven by said second gear, a fourth gear fast on said drive shaft, a fifth gear mounted on said sprocket shaft and meshing with said fourth gear, a link connecting said gear on said drive shaft with said second gear, a second link connecting said second gear with said third gear and a swinging bracket connecting said fourth gear with said fifth gear, said links and bracket being adapted to hold the gears joined by them in meshed relation, a third link pivotally connected at one end with said swinging bracket and connected at the other end to a pivot located on the center of the arc which

is described by the moving of the joint 65 whereby said link is connected to said swinging bracket when the aperture mount is shifted longitudinally without permitting a change with respect to the rotation of said sprocket, such arrangement of parts 70 being adapted to permit longitudinal movement of said aperture without changing the speed of said sprocket.

2. In a device of the character specified the combination of an aperture mount pro- 75

vided with an aperture, means for guiding a film strip across said aperture, means whereby said aperture mount is slidably sup- 80 ported in a manner such that its position may be shifted longitudinally, a sprocket 85 on said aperture mount arranged to actuate said film strip across said aperture, a sprocket shaft, a drive shaft, a gear train arranged to actuate said sprocket, said gear train comprising a gear fast on said drive shaft, a second gear driven by said gear fast on said drive shaft, a third gear driven by said second gear, a fourth gear fast mounted concentric with said third gear, a fifth gear mounted on said sprocket shaft and meshing with said fourth gear, a link connecting said gear on said drive shaft with said second gear, a second link connecting 90 said second gear with said third gear and a swinging bracket connecting said fourth gear with said fifth gear, said links and bracket being adapted to hold the gears joined by them in meshed relation, a third link pivotally connected at one end with said swinging bracket and connected at the other end to a movably mounted pivot said pivot being 95 so mounted as to be movable only along the line which is the locus of the centers of a series of arcs through which the joint of said third link and said swinging bracket may swing for various settings of said movably mounted pivot when said aperture mount is shifted longitudinally without per- 100 mitting a change with respect to the rotation of said sprocket, and means for shifting the position of said movably mounted pivot, said arrangement of parts being adapted to permit longitudinal movement 105 of said aperture without changing the speed of said sprocket and also adapted momen- 110 tarily to advance or retard the speed of said sprocket by the shifting of the position of said movably mounted pivot.

3. In a device of the character specified the combination of an aperture mount pro- 115

vided with an aperture, means for guiding a film strip across said aperture, means whereby said aperture mount is slidably sup- 120

ported in a manner such that its position may be shifted longitudinally, a sprocket on said aperture mount arranged to actuate said film strip across said aperture, a sprocket shaft, a drive shaft, a gear train

arranged to actuate said sprocket, said gear train comprising a gear fast on said drive shaft, a second gear driven by said gear fast on said drive shaft, a third gear driven by said second gear, a fourth gear fast mounted concentric with said third gear, a fifth gear mounted on said sprocket shaft and meshing with said fourth gear, a link connecting said gear on said drive shaft with said second gear, a second link connecting said second gear with said third gear and a swinging bracket connecting said fourth gear with said fifth gear, said links and bracket being adapted to hold the gears joined by them in meshed relation, a radius arm mounted to swing about a fixed pivot point and a third link joining the swinging end of said radius arm and said swinging bracket, said pivot point being so located and said radius arm being of such length that the arc described by the link joint at the swinging end thereof, when said radius arm is actuated, is the locus of the centers of the arcs through which the joint of said third link and said swinging bracket swings when said aperture mount is shifted longitudinally without permitting a change with respect to the rotation of said sprocket, and means for swinging said radius arm, such arrangement of parts being adapted to permit longitudinal movement of said aperture without changing the speed of said sprocket and also adapted momentarily to advance or retard the speed of said sprocket by the swinging of said radius arm during the period of its movement.

4. In a device of the character specified the combination of a movable variable refracting means comprising a pair of overlapping rotatable discs each made up of a plurality of refracting elements arranged to compensate the effect of downward movement of the film strip, an aperture mount slidable along the optical axis, a front objective, and means whereby said front objective is slidably mounted in a manner whereby its position may be shifted along the optical axis for the purpose of changing the equivalent focal length thereby securing exact registration of superimposed images on the screen.

5. In a device of the character specified the combination of a movable variable refracting means comprising a pair of overlapping rotatable discs each made up of a plurality of refracting elements, each of which elements is complementary to a corresponding element in the other disc, said variable refracting means being arranged to compensate the effect of downward movement of the film strip, a front objective and a diaphragm located between said variable refracting means and said front objective and placed symmetrically on the optical axis, said dia-

phragm being provided with V shaped projections from its top and bottom and arranged to narrow the zone of action of a pair of said complementary elements to a limited area centered upon the optical axis.

6. In a device of the character specified the combination of a pair of overlapping rotatable discs each made up of a plurality of sectors each of which sectors is cut from a separate lens blank and so arranged that the optical centers of complementary sectors successively coincide within the area whereon said sectors overlap upon rotation of said discs, a front objective, and a diaphragm located between said variable refracting means and said front objective and placed symmetrically on the optical axis, said diaphragm being provided with inwardly directed V-shaped projections from its top and bottom and arranged to narrow the zone of action of a pair of said complementary sectors to a limited area centered upon the optical axis.

7. In a device of the character specified the combination of a movable variable refracting means comprising a pair of overlapping rotatable discs each made up of a plurality of refracting elements arranged to compensate the effect of downward movement of the film strip, a front objective, and a diaphragm in front of said objective, the aperture of said diaphragm having sides each corresponding in curvature and alignment with the outer periphery of one of said overlapping rotatable discs, the vertical dimension of said aperture diminishing toward the center thereof, said diaphragm being thereby adapted to so equalize illumination reaching the screen that it may be of uniform unvarying intensity.

8. In a device of the character specified the combination of a movable variable refracting means comprising a pair of overlapping rotatable discs each made up of a plurality of refracting elements, each of which elements is complementary to a corresponding element in the other disc, said variable refracting means being arranged to compensate the effect of downward movement of the film strip, a front objective and a diaphragm located between said variable refracting means and said front objective and placed symmetrically on the optical axis, and arranged to narrow the zone of action of a pair of said complementary elements to a limited area centered upon the optical axis, and a second diaphragm located in front of said objective, the aperture of said diaphragm having sides each corresponding in curvature and alignment with the outer periphery of one of said overlapping rotatable discs, the vertical dimensions of said aperture diminishing toward the center thereof, said diaphragm being thereby

- adapted to so equalize illumination reaching the screen that it may be of uniform unvarying intensity.
9. In a device of the character specified
 5 the combination of a pair of rotatable optical rectifying members each composed of a plurality of elements arranged to co-act with corresponding elements in the other of said members, a pair of rotatable shafts on
 10 one of which each of said optical rectifying members is mounted, worm wheels on each of said shafts, a cross-shaft, a pair of opposite acting worm gears on said cross-shaft each of which meshes with one of said
 15 worm wheels, and means whereby said shaft may be moved longitudinally in either direction, to bring said co-acting elements into exact registration, and may be secured in any desired position.
- 20 10. In a device of the character specified the combination of a movable variable refracting means comprising a pair of overlapping rotatable discs each composed of a plurality of optical elements symmetrically
 25 placed so that their adjacent edges are radial, and a plurality of opaque patches each of which is placed symmetrically across a pair of adjacent radial edges near the outer periphery of each of said discs.
- 30 11. In a device of the character specified the combination of a movable variable refracting means comprising a pair of overlapping rotatable discs each composed of a plurality of optical elements symmetrically
 35 placed so that their adjacent edges are radial, a plurality of opaque patches each of which is placed symmetrically across a pair of adjacent radial edges near the outer periphery of each of said discs and is so
 40 shaped with its edges regularly converging toward said radial edges that the upper edges of a pair of adjacent patches approaching the optical axis form a variable obtuse angle, and the lower edges of said
 45 opaque patches likewise form a variable obtuse angle while said patches are departing from the optical axis, and a symmetrical diaphragm provided at its top and bottom with inwardly directed V portions, the
 50 angles formed by said upper and lower edges of said patches corresponding respectively to the angle of an adjacent V portion of said diaphragm at the moment when said patches clear said top V portion, or
 55 commence to overlap said lower V portion.
12. In a device of the character specified the combination of a movable variable refracting means comprising a pair of overlapping rotatable discs each composed of a plurality of optical elements symmetrically placed so that their adjacent edges are radial, a plurality of opaque patches each of which is placed symmetrically across a pair of adjacent radial edges near the outer periphery of each of said discs and is so
 60 shaped with its edges regularly converging toward said radial edges that the upper edges of a pair of adjacent patches approaching the optical axis form an obtuse angle, a diaphragm provided at its top and bottom with inwardly directed V portions the angle of which is substantially that of said obtuse angle, a front objective, and a second diaphragm located in front of said objective, said second diaphragm having an aperture each side of which corresponds in curvature and alignment with the outer periphery of one of said overlapping rotatable discs, the vertical dimension of said aperture diminishing toward the center thereof, said diaphragm being thereby adapted to so equalize illumination reaching the screen that it may be of uniform, unvarying intensity.
- 70 13. In a device of the character specified the combination of a hub, an annular spider mounted on said hub and provided with an annular shoulder and an annular clamping face, a plurality of sectors each of which is cut from a separate lens blank, a plurality of clamps corresponding in number to the number of said sectors, said clamps being arranged to butt against said annular shoulder, and each one thereof being positioned to overlie the inner portion of one of said sectors which is there provided with parallel faces, a plurality of screws each of which is arranged to draw one of said clamps toward said spider and a plurality of dowel pins fixed in said spider.
- 75 14. In a device of the character specified the combination of a hub, an annular spider mounted on said hub and provided with an annular shoulder and an annular clamping face, a plurality of sectors each of which is cut from a separate lens blank, a plurality of clamps corresponding in number to the number of said sectors, said clamps being arranged to butt against said annular shoulder, and each one thereof being positioned to overlie the inner portion of one of said sectors which is there provided with parallel faces, a plurality of screws each of which is arranged to draw one of said clamps toward said spider, a plurality of dowel pins fixed in said spider, and paper pads between said lens sectors and the clamping faces of said spider and said clamps.
- 80 15. In a device of the character specified the combination of a movable variable refracting means comprising a pair of overlapping rotatable discs each composed of a plurality of optical elements symmetrically placed so that their adjacent edges are radial, a front objective immovable in a plane perpendicular to the optical axis, and a diaphragm located between said variable refracting means and said front objective and placed symmetrically on the optical axis.
- 85 90 95 100 105 110 115 120 125 130

and provided with inwardly directed V-shaped projections at its top and bottom, the number of optical elements on each disc and the proportions of said V-shaped projections on said diaphragm being so arranged that the angle formed at the center of a disc by the radii passing through the

optical axis and through the upper radial edge of an optical element at the instant when the lower radial edge of the same optical element enters the unobstructed beam of light will not be substantially in excess of 29 degrees. 10

ARTHUR J. HOLMAN.
